REAMER ATTACHMENT

Americo Dantry, Cecil, Pa.

Application August 6, 1937, Serial No. 157,815
Renewed December 6, 1939

1 Claim. (Cl. 77—73.5)

This invention appertains to new and useful improvements in reamers and more particularly to pipe reamers.

The principal object of the present invention is to provide a reamer attachment for thread dies whereby both the reaming and threading operations can be performed simultaneously.

Other important objects and advantages of the invention will become apparent to the reader of the following specification.

In the drawing:

Figure 1 represents a side elevational view of the attachment.

Figure 2 is an end elevational view.

Figure 3 is a longitudinal sectional view through the assembly.

Figure 4 is a fragmentary detailed sectional view of the reamer element.

Referring to the drawing wherein like numerals designate like parts, it can be seen that numeral 5 denotes a barrel provided with the longitudinally extending slot 6 in the side wall thereof. The barrel 5 is closed at one end and at its opposite end provided with the U-shaped extension 7 having the foot portions 8—9. These foot portions 8—9 are provided with slideways 10 extending into the same from the side edges thereof. These slots are to receive the securing means of the thread die.

Numerals 11 denotes the reamer head provided with the shank 12 extending into the barrel 5.

The shank 12 is provided with the lateral stem 13 provided with the head 14. This stem can be engaged into either the notch 15 or the notch 16 depending upon the extent of the threading operation and the consequent reaming requirement. 5

While the foregoing specification sets forth the invention in specific terms, it is to be understood that numerous changes in the shape, size and materials may be resorted to without departing from the spirit and scope of the invention as claimed 10 hereinafter.

Having described the invention what is claimed as new is:

A reamer attachment for thread dies comprising a barrel, mounting means for the barrel, said barrel being provided with a longitudinally extending slot therein, a reaming head provided with a shank slidably disposed in the barrel, the upper end of the barrel being closed, a spring interposed between the closed end of the barrel and the inner end of the shank, said shank being provided with a threaded opening, a pin provided with a threaded end for threaded engagement in the threaded bore, said pin being disposed through the slot in the barrel and provided with a finger engageable knob at its outer end, said barrel at the edge portion of the slot being provided with oblique notches for receiving the said pin disposed in a backward direction. 15 20 25 30
